UNITED STATES PATENT OFFICE.

JOHN P. CROASDALE, OF BERWYN, PENNSYLVANIA.

REFLECTOR ELEMENT.

Application filed June 4, 1921. Serial No. 474,998.

To all whom it may concern:

Be it known that I, JOHN P. CROASDALE, a citizen of the United States, residing at Berwyn, in the county of Chester and State 5 of Pennsylvania, have invented a new and useful Reflector Element, of which the following is a specification.

The invention relates to non-glare headlights or devices for overcoming the blinding glare of an automobile headlight, and at the same time for increasing its lighting efficiency.

As is well known, the usual automobile headlight comprises a parabolic reflector. 15 With the light source in front of the focus, part of the light reflected from the lower half of the reflector is thrown forwardly and upwardly and the light reflected from the upper half is thrown forwardly and 20 downwardly. With the light source behind the focus, part of the light from the upper half of the reflector is thrown upwardly, and from the lower half downwardly. Eliminate the reflected rays that 25 are reflected upwardly, and no rays will be projected above the height of the lamp. This can be accomplished by destroying the reflecting character of the portion that tends to reflect upwardly, but the lighting efficiency of the headlight is thereby greatly 30 reduced. Various lenses have been employed for deflecting or modifying the rays reflected upwardly, but these usually impair the lighting efficiency to about the same extent as they modify the glare.

The present invention, applied for example to a headlight having the lamp in front of the focus, comprises improved means for deflecting, to the upper half of 40 the reflector, the rays that would normally strike the lower half, whereby these rays are also reflected forwardly and downwardly.

Thus we have all the rays from the lamp directed to the upper half of the reflector 45 and thence reflected forwardly and downwardly. No rays are directed above the height of the headlight, and so there is no blinding glare to the passing traveler. Practically no rays are dissipated into the 50 upper spaces; all the rays are utilized and concentrated on the road in front of the car; and so the efficiency is substantially in-

creased while the objectionable glare is eliminated.

It is the object of the present invention 55 to provide means for accomplishing the results above proposed, which shall be simple in construction, readily and cheaply produced on a commercial scale, and which shall be so proportioned and arranged, that the rays which would normally be directed upwardly, shall be so reflected as will result in the precise and efficient reflection of all the rays from the source of light, below a required horizontal plane and to and 60 upon such spaces and surfaces as shall be most desirable in navigating the car at night, so that the light, instead of being impaired will be intensified and so that all glare above said horizontal plane will be 65 eliminated. By the means herein described, this result is secured, notwithstanding a substantial variation in the position of the lamp from its theoretically focal point.

Referring to the drawings, which illustrate merely by way of example suitable means for effecting my invention;—

Fig. 1 is a front elevation of a headlight containing the invention.

Fig. 2 is a section on line 2—2 of Fig. 1.

Fig. 3 is a view in perspective of the reflector element removed from the headlight.

Fig. 4 is a similar view of a modification.

Figs. 5, 6 and 7 are plan views of separate strips or blanks from which the completed deflector element may be constructed.

Fig. 8 is a plan view of an integral blank from which the completed deflector element may be formed.

Similar numerals refer to similar parts throughout the several views.

As an embodiment of my invention, by way of example, I provide a plurality of strips, such as 8, 9 in Figs. 1 and 3, or 8, 9 and 16, as in Fig. 4, forming reflecting surfaces or areas. These strips are so bent that their longitudinal margins will lie in arcs having an approximately common axis which corresponds to the axis of the parabolic reflector of the headlight or the horizontal axis of the lamp. The rear margins of said strips are in close proximity to the headlight reflector surface as shown, that is in contour with said headlight reflector sur-

face. One or more of these strips, due to their original shape, as in Fig. 6, are arranged or formed so that, in the direction of their cross-section their reflecting surfaces are inclined to the horizontal axis of the lamp, and the several strips are relatively at different inclinations. In other words, a flat strip such as shown in Fig. 6, when bent or curved as just described, forms a segment theoretically cut from a cylinder, in planes inclined to the axis of the cylinder.

All of the strips are so disposed and arranged that the reflecting surface of each will reflect or deflect all of the rays, incident to said surface from the source of light, to the upper surface of the headlight reflector.

As a concrete example, I have found that two reflector strips serve the purpose well for many forms of standard parabolic headlights.

In accordance with the present invention, all of the light from the lamp is utilized, none is modified or obscured by prisms or lenses, or other light obscuring devices. This is made possible by having all the rays of light, emanating from the lamp, projected forwardly and downwardly. In this way the full illuminating power of the lamp is utilized, by projecting the entire light derived therefrom, forwardly and downwardly upon the road or path of travel of the car, thus greatly increasing the light projected by the headlight and at the same time preventing any of the rays being projected above the level of the headlight, but without impairing the horizontal flare below said level, so that a person either walking, or traveling in a car, in the opposite direction is totally unaffected by the glare therefrom.

Referring especially to Figs. 1 and 3, I show two reflector strips 8 and 9. These are formed in semi-circular arcs having a common axis corresponding to the horizontal axis of the lamp 10, and also to the axis of the parabola of the headlight reflector 11. The strip 8, being just beneath the lamp is substantially cylindrical in form, and the line 12 indicates the general direction of the reflected rays from filament 13 of lamp 10, first striking the reflecting surface of strip 8, thence deflected to the upper reflector portion 11, and thence re-reflected forwardly and downwardly. Lines 14 and 15 indicate the general direction of the rays from filament 13 which, clearing reflector 8, reach reflector strip 9, thence reflected to upper reflector half 11, and thence re-reflected forwardly and downwardly as indicated. While I have shown only two reflecting strips 8 and 9 in Figs. 1 and 3, it will be obvious that different numbers of such strips may be used, depending upon various conditions, such for example as the size or di-

mensions of the headlight, or a desire to secure a wider distribution of the rays reflected or deflected from beneath the horizontal axis of the lamp to the upper reflector half. For example, in Fig. 4 three strips, 8, 9 and 16 are shown.

In Figs. 3 and 4, I show reflector elements built up of strips suitably fastened together. The strips 8 and 9 in Fig. 3, and 8, 9 and 16 in Fig. 4, are preferably connected together, in any suitable way, for example by the element 17 having the semi-circular front portion 17^a, adapted in operative position to be in a substantially vertical plane, and the wings 17^b in a substantially horizontal plane. The strip 8 is secured to the ends of the wings 17^b as indicated. The other strip or strips being secured between strips 8 and 9 as shown. From the rear middle part of strip 8 is provided the arm 18 with the forked formation 19 for engaging beneath the neck of the lamp. While at the lower middle portion of 17^a is provided the projection 20 adapted to engage a suitable recess, formed for the purpose, in the lower portion of the headlight body, for securing and maintaining said deflector element in proper position.

In Fig. 6 is shown the blank or form of strip 9 or 16, when cut from a flat sheet of metal. Upon bending this strip into a semi-circular arc, its reflecting surface is inclined as to its cross-section, to the horizontal axis of the lamp as clearly shown in Fig. 2. In Fig. 7 is shown the general formation of a blank suitable for forming the element 17, while Fig. 5 shows a suitable blank for strip 8 and arm 18.

I have shown in Figs. 3 to 7 inclusive, suitable blanks and the method of bending and assembling same to form a deflector element embodying my invention. I have found this an extremely simple inexpensive and efficient method and means for effecting my invention.

In Fig. 8, I have shown an integral blank, which may be bent and secured together at its two free ends to form the structure shown in Fig. 3, except that the strip 17^a is omitted, and the extensions 17^b are integral with strip 9. The point or lug 20 being formed on an extension from the middle upper part of strip 9.

It will be understood however, that the above embodiments are given merely as examples, and that various other methods and means may be employed for securing the necessary reflecting surfaces properly associated, disposed and arranged relatively to the lamp filament which are the essentials of my invention as defined in the following claim.

What I claim is:—

In combination with a headlight reflector, a plurality of separated reflector-surface-

forming strips curved as to their longitudinal extensions in approximate arcs of circles having their axes on the horizontal axis of the headlight reflector, and their several rear edges in close proximity to and in contour with the headlight reflector surface, and so positioned that their reflecting surfaces shall intercept rays that would normally be reflected upwardly from the surface of the headlight reflector, to the effect that approximately all rays shall be projected below a given elevation. 10

JNO. P. CROASDALE.
